Primary Examiner — Cathy A MacCormac*(74) Attorney, Agent, or Firm* — Stephen G Stanton, Esq.(57) **CLAIM**

The ornamental design for a pet cot, as described and shown in the accompanying drawings.

DESCRIPTION

FIG. 1 is a front perspective view of a pet cot in accordance with an exemplary embodiment of the present invention; FIG. 2 is a rear view of the pet cot shown in FIG. 1; FIG. 3 is a front view of the pet cot shown in FIG. 1; FIG. 4 is a right side view of the pet cot shown in FIG. 1, with the left side being a mirror image of the right side shown; FIG. 5 is a top plan view of the pet cot shown in FIG. 1; FIG. 6 is a bottom view of the pet cot shown in FIG. 1; FIG. 7 is a rear perspective view of the pet cot shown in FIG. 1;

FIG. 8 is a rear perspective view of a second embodiment all other views are the same as FIGS. 1-7 the only difference being the appearance of the dual rear vertical support structures; and,

FIG. 9 is a rear perspective view of a third embodiment all other views are the same as FIGS. 1-7 the only difference being the appearance of the dual rear vertical support structures.

The broken lines present in the FIGURES are for illustration only, and do not form a part of the claimed design.
